MECHANISM FOR DEPOSITING CONFETIONS ON WAFERS

John Brandt, Chicago, Ill., assignor to Salerno Machinery Company, Chicago, Ill., a corporation of Illinois

Application June 24, 1937, Serial No. 150,099

4 Claims. (Cl. 107—28)

My invention relates to machines for depositing coatings of soft plastic confections, such as icings, jellies, and the like upon baked wafers or cookies to produce coated or deposit goods. The 5 present invention relates to improvements in the depositing mechanism of such a machine as that shown in Salerno Patent No. 1,801,573, dated April 21, 1931, and has to do with changes brought about by the provision of additional parts whereby the functioning of the depositing mechanisms 10 is made more uniform and regular. In the following specification I have described my present invention and improvement together with such other parts of the machine improved upon as will 15 be necessary for a clear understanding of the same, and in the appended claims I have set forth the essential elements of my invention.

In the accompanying drawings Figure 1 is a vertical section in a plane extending transversely of the hopper and longitudinally of the machine, the plane of the section being indicated by the dotted line 1—1 on Fig. 3;

Fig. 2 is a left side elevation of the same portion of the machine shown in Fig. 1;

Fig. 3 is a rear elevation of the upper portion of the machine viewed from a plane just to the rear of the hopper structure, parts of the hopper casing being broken away to show parts behind them; and

Fig. 4 is a detail vertical section showing my invention applied to the icing mechanism only, and showing a position of the forcing plunger and valve opposite to that shown in Fig. 1.

Like reference characters identify like parts in 35 all the figures of the drawings.

For the purpose of facilitating an understanding of the present invention a brief preliminary description of the organization of the machine will first be given.

The wafers to be deposited are carried forwardly through the machine on an endless intermittently movable feed belt 1 passing over the top of a rocking table 2, which is given an intermittent lifting movement of determinable extent to bring the rows of wafers, one row at a time, into proximity with a cross-row of depositing nozzles, the depositing operations occurring at the periods of rest of the belt in its forward movement.

The deposits of one confection are made through a central nozzle *a* having valve-governed communication with one supply hopper,—in the present instance the larger one, usually used for the deposit of icing,—and the other a concentric 55 outer nozzle providing an annular passage, also

valve-governed, leading to the smaller hopper, which may be termed the jelly hopper. Associated with each hopper is a reciprocating plunger or pumping member cooperating with the valve member of the particular hopper to pump 5 charges of confection from such hopper through the nozzles to coat the cakes.

As in the case of the machine described in said Salerno Patent No. 1,801,573, the hopper structure is formed with an approximately central 10 partition 23, separating the icing hopper from the jelly hopper, and a stationary rear forcing chamber wall 24 and a stationary front forcing chamber wall 25, both parallel with the partition wall 23, and with the intersecting hopper walls 15 at the ends of the hopper providing two forcing chambers within which severally work the vertically reciprocating flat piston or plunger 26 of the jelly depositing mechanism, and the similar plunger or piston 27 of the icing depositing 20 mechanism. Below the plunger 26 and rotatably mounted in the stationary members of the forcing mechanism is arranged the rotary flat-sided valve member 28 of the jelly depositing mechanism and the similar rotary valve 29 of the icing depositing 25 mechanism, each provided with teeth forming a gear at one end of the valve member and the toothed portions of the two members being disposed at opposite sides of the machine.

The icing plunger or piston member 27 is reciprocated by means of a pair of eccentrics 40 on a driven shaft 32, vertical connecting bars 41, rocking adjusting frames 42, and a pair of connecting rods 44 pivoted to opposite ends of a cross-head 45 slidably mounted in a guide frame 35 47 above the double hopper structure, and connected by bolts 46 to the upper side of the piston.

The icing valve 29 is rotated in synchronism with the piston movements through a cam 52 secured to the shaft 32, a rocking lever 54, a connecting rod 56, and a bell-crank 57 having a vertical member 57^a connected to a sliding horizontal rack-bar 58 cooperating with the toothed end of said valve 29. The timing of the plunger and valve movement is such that the plunger will 45 begin to ascend an instant before the valve closes communication through the nozzles, with the result that formation of a nipple of confection upon the top of the deposit is prevented.

The jelly plunger or piston 26 is operated 50 through a cam 59 adjustably secured (through means not illustrated) to the shaft 32, a rocking adjusting frame 60, a connecting rod 61, a rock arm 62 and rock shaft 63 carrying a pair of rock arms 64—64 connected by links 65—65 to a cross- 55

head 66 slidingly mounted in the guide frame 41 and connected by vertical bars 67 with the piston.

The jelly valve 28 is operated by a cam 68, also adjustably secured to the shaft 32 through means for simultaneous adjustment with the cam 59 through means not illustrated, a rocking lever 69, a connecting rod 70, and a bell crank 71 having a vertical arm connected to a sliding horizontal rack-bar 72 arranged to mesh with the toothed 10 end of said jelly valve.

The table 2, it may be stated, is supported and intermittently lifted to a determinable extent through a triple-faced cam adjustably secured to a shaft 93 having geared connection with the 15 shaft 32, and arranged through a cooperating cam roller carried by arms 88 upon a yoke 85 loosely mounted on a rock shaft 55 and through a lug 86 on said yoke and a block 83 secured to such rock shaft to rock such shaft and a pair of 20 arms 82 also secured thereto, and through a pair of links 81 pivoted to the ends of such arms to raise and lower the table to an extent determined by the particular face of the cam.

Coming now to the modified construction of 25 the depositing mechanism which forms the subject matter of the present invention, it will be understood that my invention may be applied either to the icing depositing mechanism, or the jelly depositing mechanism, or both. In depositing 30 machines of the prior art, constructed in accordance with the disclosure and teaching of the Salerno patent above mentioned, it has been found in practice that certain defects exist, found usually to a greater extent in the icing depositing mechanism than the jelly depositing 35 mechanism, though in some measure inherent in both. The icing (or other confection) in some instances tends to thicken, and clog around the entrance passage to the rotary valve, particularly 40 when a somewhat stiff and heavy confection is being operated upon, and it is frequently necessary to manually scrape down the partially caked matter from the sides of the hopper and stir it up in this region. Another defect arises from 45 the fact that when operating the machine at full speed the suction induced by the upward movement of the piston in the forcing chamber immediately after the momentary initial suction which draws back the final nipple of confection 50 from the top of the deposit and at the time the valve is beginning to open communication between the supply hopper and the forcing chamber, is under some circumstances insufficient to induce a free and rapid flow of the somewhat 55 thick and viscid confection into such chamber sufficient to entirely fill it during the upward movement of the piston, with the result that a rarefied void remains which upon the next downward movement of the piston acts to produce an 60 imperfect and wrinkled deposit of confection upon the wafers. Should the confection be unusually stiff, and become clotted, the tendency to imperfect functioning of the machine is further intensified. It is the object of my invention 65 to maintain a smooth uniform consistence of the confection adjacent the lowermost portion of the hopper, and bring about a free and adequate flow of the confection from the hopper into the forcing chamber to fill it properly under all 70 conditions, so that when the charge from the chamber is forced through the valve and nozzles of the machine perfectly formed deposits of confection will be made.

To this end, and describing first the mechanism 75 for depositing the icing, I provide a supplemen-

tary pumping member consisting of a vertically reciprocating plunger 100 arranged immediately above the valve opening covered and uncovered by the icing valve 29, this plunger being housed in a chamber formed by the forward face of the front forcing chamber wall 25, and a second parallel forward wall 101 secured to the hopper walls at the sides of the machine, and the portions of such side hopper walls lying between the walls 25 and 101.

This supplementary pumping member 100 is arranged to move downwardly as the plunger 27 moves upwardly and while the valve 29 opens communication between the hopper and the forcing chamber, and to move upwardly while communication is closed between the hopper and forcing chamber and while the confection is being extruded through the valve passage and depositing nozzles. The result is a vigorous pumping action of the confection as it is pumped into and out of the pumping chamber below the plunger 100, which upon the downward stroke of the plunger drives the confection beneath it in one stream toward and through the valve opening and at the same time drives excess confection in another stream underneath the partition 101, and upon the upward stroke of the plunger draws the confection into space below, and then exerts a stirring effect on the confection adjacent the valve opening which aids materially in keeping the confection of uniform consistency and free from clots tending to cause irregularity in the functioning of the forcing and valve mechanism.

To effect the described movement of the supplemental pumping member 100, I have provided 35 a pair of oscillating levers 102—102, which are intermediately pivoted upon a cross-bar 103 extending between and secured to the side walls of the hopper structure, the levers being pivotally connected at their inner ends to links 104—104 40 which are pivoted also to the cross-head 45 of the icing depositing mechanism and at their outer ends are pivoted to links 104^a pivotally connected with lugs formed on the top of the member 100.

The mechanism for depositing the jelly or other confection is substantially the same in construction and arrangement, and includes the supplementary pumping member 105, reciprocating in a chamber enclosed by the forcing chamber 50 wall 24 and a parallel rear wall 106 and portions of the side walls of the jelly hopper, the pumping member being reciprocated by means of a pair of oscillating levers 107—107 intermediately pivoted to a stationary cross-bar 108, 55 and connected by links 109—109 pivoted to the cross-head 66 of the jelly plunger mechanism and by links 110—110 pivoted to lugs upon the top of such plunger member.

It will be noted that whatever be the timing 60 of the icing depositing mechanism with respect to the jelly depositing mechanism, the connections described will at all times cause the supplemental plungers 100 and 105 to operate in synchronism with the movements of the respective associated forcing plungers 27 and 26.

I claim:

1. In a confection-depositing machine, a confection hopper having an outlet opening adjacent its bottom, a row of depositing nozzles adjacent 70 said outlet opening, a forcing chamber having an opening adjacent said outlet opening of the hopper, a reciprocating piston closing said chamber above its opening, a valve seated in the hopper structure and arranged to control communica- 75

tion alternatively between said piston chamber and said hopper and between said piston chamber and said nozzles, means for operating said piston and said valve synchronously, a pumping chamber having an opening in said hopper adjacent said outlet opening of the hopper, a plunger in said pumping chamber, and means for reciprocating said plunger to expel confection from said pumping chamber when said valve is open between said hopper and said forcing chamber and to draw confection into said pumping chamber when said valve is closed between said hopper and said forcing chamber.

2. In a confection-depositing machine, a confection hopper having an outlet opening adjacent its bottom, a row of depositing nozzles adjacent said outlet opening, a flat vertical rectangular forcing chamber having a bottom opening adjacent said outlet opening of the hopper, a reciprocating flat piston closing said chamber above its opening, a valve seated in the hopper structure and arranged to control communication alternatively between said piston chamber and said hopper and between said piston chamber and said nozzles, means for operating said piston

chamber and said valve synchronously, a pumping chamber having an opening in said hopper adjacent said outlet opening of the hopper, a plunger in said pumping chamber, and means for reciprocating said plunger to expel confection from said pumping chamber when said valve is open between said hopper and said forcing chamber and to draw confection into said pumping chamber when said valve is closed between said hopper and said forcing chamber.

3. Confection-depositing mechanism according to claim 1 in which the means for reciprocating the plunger in the pumping chamber comprises linkage intermediate the recited piston and said plunger.

4. Confection-depositing mechanism according to claim 1 in which the means for reciprocating the plunger in the pumping chamber comprises a pair of oscillating levers intermediately pivoted upon a stationary part of the hopper structure and a pair of links pivoted to the ends of said levers and also pivoted to the recited piston, and a pair of links pivoted to the other ends of said levers and also pivoted to said plunger.

JOHN BRANDT. 25
